UNITED STATES PATENT OFFICE.

MERTON PARKER, OF GLENDALE, CALIFORNIA.

COLLAR-CLIP.

1,325,411.

Specification of Letters Patent. Patented Dec. 16, 1919.

Application filed January 22, 1919. Serial No. 272,436.

To all whom it may concern:

Be it known that I, MERTON PARKER, a citizen of the United States, residing at Glendale, in the county of Los Angeles and

5 State of California, have invented a new and useful Improvement in Collar-Clips, of which the following is a specification.

My invention relates to a collar clip or holder and has particular reference to a device of this character adapted to be passed through the vertical or horizontal back button holes of the shirt band and collar; and the objects of my improvement are to provide a clip or device of the above mentioned character, which will lie perfectly flat and may be used in connection with shirts and collars having vertical and horizontal back button holes of different sizes, will at all times prevent the collar from being accidentally unfastened, or the clip from becoming accidentally unfastened from the shirt band after the collar is removed.

I attain these objects by the combination of parts and their arrangement illustrated 25 in the accompanying drawing, in which—

Figure 1 is a back view of the shirt band, provided with a horizontal button hole, showing the clip arranged therein; Fig. 2, is a view of collar, with part of lap cut away, 30 showing a collar having a horizontal button hole attached to the shirt band with the clip; Fig. 3, is a view of a shirt band provided with a vertical button hole, showing the clip arranged; also as the clip would 35 appear in place in the vertical back hole of a collar; Fig. 4, is a plan view showing the outward and vertical inclination of the shank 9 and the curvature of the entire clip; and, Fig. 5, is a perspective view of same.

40 Similar numerals refer to similar parts throughout the several views.

In the drawings, wherein is illustrated a preferred embodiment of my invention, the numeral 1 designates a portion of a shirt 45 provided with the usual band 2. This shirt band has its outer fold 3 at the back portion of said shirt provided with a horizontally arranged button hole 4, or vertically arranged buttonhole 5, as shown; numeral 6, 50 shows the collar back, or lap, cut away, showing the clip in the horizontal button hole 7, of collar, while 5 shows distended vertical button hole with clip in place as it would appear in both a shirt band and 55 collar band provided with a vertically arranged button hole.

My clip or holder comprises a horizontally arranged body portion or elongated plate 8, which is curved longitudinally in a horizontal plane, to conform generally to the 60 curvature of the shirt band and collar, whereby the same will lie perfectly flat within the shirt band. Depending from the body portion 8, and equidistantly spaced from the ends thereof, is an L-shaped portion comprising a relatively short shank 9, which is vertically inclined or disposed at an angle with relation to the horizontal body portion, as shown.

Formed upon the free or lower end of 70 this shank 9 is a horizontal head 10, forming the horizontal arm of the L-shaped portion, which extends laterally beyond the shank 9 in one direction only, in the plane of the shank 9 and in a plane substantially parallel to the end portion of the horizontal body portion of the elongated plate 8. Relatively a short space from shank 9 depends from elongated plate 8, a guard 11, and a relatively short space farther, with one side 80 flush with one end of the plate 8, extends guard 12. These guards 11 and 12 are preferably of a length extending to the bottom of the arm or head 10.

These guards in combination with other 85 parts of the clip are considered the most important features of the invention, as it is obvious that if the shank is made sufficiently small to permit its use in a vertical button hole, it can not hold a collar to the 90 shirt band where both band and collar are provided with horizontal button holes. By employing the guard 11 in conjunction with the shank 9, the one side of the horizontal button hole in the shirt band is filled, there- 95 by holding the shank 9 in the center of shirt band and collar. This combination and arrangement permits of the making of the head 10 relatively narrow and short; at the same time when the clip is used in a 100 horizontally arranged button hole in the back of the collar the guard pinches against the collar, thereby holding said collar more firmly. The function of the guard 12, is keeping, or holding, the button erect within 105 the walls of the shirt band and to prevent the button from turning within these walls and falling out.

As is shown by the drawings, all parts of the clip are preferably formed integral, the 110 same being preferably stamped from a piece of suitably thin and stiff sheet metal, or like,

and curved longitudinally in a horizontal plane to conform generally to the curvature of the shirt band and collar.

In the use of the clip, the horizontal head 10 is passed through the vertical button hole 5, or through the horizontal button-hole 7 are passed both the horizontal head 10 and the guard 11, to be disposed outwardly of the shirt band as shown in Figs. 1 and 3. 10 The collar is then manipulated so that the horizontal head is passed through a vertical button hole in the collar, or horizontal button hole 7 of collar, as shown in Fig. 2.

With the foregoing shown and described 15 combination and arrangement embodied in a clip, means are provided for its use in connection with any collar now on the market.

It is understood that the form of my invention herewith shown and described is to 20 be taken as a preferred example of the same, and that certain changes in the shape, size and arrangement of parts may be resorted to without departing from the spirit of the invention or the scope of the subjoined 25 claims.

I am aware that prior to my invention collar clips or holders have been made having a shank depending from the body equidistantly from the ends of such body, 30 and that said shanks were inclined outwardly from the body portion, and were provided with a longitudinal head and that all parts of the clip were curved longitudinally in a horizontal plane. I therefore do not 35 claim such a combination broadly; but

I claim:

1. The combination in a substantially flat

integral sheet metal collar button, comprising an upper body-plate curved slightly to conform to the curvature of a collar when 40 arranged substantially horizontally; a depending shank integral with the lower edge of the body plate at a point substantially equidistantly spaced from the opposite ends thereof and vertically inclined outwardly 45 and downwardly with respect to the body plate; and a relatively long head integral with the lower outer end of the depending shank, said head being spaced vertically a substantial distance from the body plate and 50 curved slightly longitudinally to be substantially concentric with the curved body plate and conform to the curvature of the collar, said head extending in one direction laterally beyond the shank and longitudinally of the 55 body plate; a depending guard integral with the lower edge of the body plate, said guard being spaced a substantial distance from the shank, and extending a substantial distance from the body plate, and a depending 60 guard integral with the lower edge of the body plate, said guard spaced a substantial distance from the other guard and the outer edge of guard terminating with the 65 contiguous end edge of the upper body; the guard to extend a substantial distance from the body plate.

2. In combination with a flat integral sheet metal, or like stiff material, collar clip comprising an upper body plate, a depending shank and longitudinal head, guards 11 and 12 substantially as shown and described. 70

MERTON PARKER.
